UNITED STATES PATENT OFFICE.

JOSEPH BECKER, OF PITTSBURGH, PENNSYLVANIA, ASSIGNOR TO THE KOPPERS COMPANY, OF PITTSBURGH, PENNSYLVANIA, A CORPORATION OF PENNSYLVANIA.

COKE-HANDLING APPARATUS.

Original application filed April 23, 1920, Serial No. 376,126. Divided and this application filed April 18, 1922. Serial No. 555,149.

This invention relates to coke handling apparatus, and has for its object to provide means for quenching the hot coke as soon as it is discharged from the coking chambers, such as retort coke ovens, without resort to expensive quenching car apparatus for carrying the coke away to quenching stations, as commonly employed; to provide conveyer means for carrying the coke away, as soon as it is quenched, and also to provide for discharging the water employed in the quenching in such manner as to substantially prevent the discharge of water on to the conveyer means.

In addition to the general objects recited above, the invention has for further objects such other improvements or advantages in construction and operation as are found to obtain in the structures and devices hereinafter described or claimed.

In the accompanying drawings, forming a part of this specification, and showing, for purposes of exemplification, a preferred form and manner in which the invention may be embodied and practiced, but without limiting the claimed invention specifically to such illustrative instance or instances:

Figure 1 is a general view of a small coking plant embodying features above specified and equipped with the improved coke handling apparatus of the present invention, the view being taken on vertical planes crosswise of the plant through a coking chamber, the regenerators, the quenching wharf and other parts;

Fig. 2 is an enlarged vertical sectional elevation of the coke handling apparatus; and

Fig. 3 is a perspective view of the coking plant and further illustrating the coke handling apparatus.

Fig. 4 is a side elevational view in a large scale, parts being shown in section, of mechanism at the lower end of the coke wharf showing the gate 83 in closed position.

Fig. 5 is a view similar to Fig. 4, but showing the gate 83 in open position.

The same characters of reference designate the same parts in each of the several views of the drawings.

Because of its simplicity in construction and relative economy, as compared with the quenching car apparatus and quenching sta-

tions commonly employed, the invention is of particular utility in conjunction with small coking plants, such as is illustrated in the accompanying drawings and having features of the wellknown Koppers cross-regenerative type of coking retort oven, exemplified in the patent to H. Koppers, No. 818,033 dated April 19, 1906 and in my pending application for Letters Patent of the United States for coking retort oven Serial No. 376,126, filed April 23, 1920 of which this application is a division. For convenience, the present description will be confined to the illustrated embodiment of the invention; features of construction and operation are, however, capable of other valuable applications, for example, to coking plants of whatever magnitude. Consequently the invention is not confined in its scope to the specific use and specific embodiment herein described as an illustrative example.

Referring to the drawings, there are illustrated sectional views of a coke oven battery or plant of the by-product type, such as has been hereinbefore mentioned. The coke oven battery or plant embodies in its construction a plurality of crosswise elongated heating walls 11, 11 and a plurality of intermediate crosswise elongated horizontal coking chambers or ovens 12, 12. The heating walls 11 form the side walls of the respective coking chambers 12, as shown more particularly in Fig. 3. The coal to be coked is elevated by means of an elevator indicated generally at 15 into the coal hoppers 16 which are supported by a superstructure above the top of the battery of ovens or retorts 12. Running on a track 17 on the top of the oven battery is a larry car 18 which receives coal from the hoppers 16 and charges the several coking chambers or ovens 12 through charging holes 19 located in the top 20 of the oven battery and positioned directly above the ovens or chambers 12. These charging holes 19 are equipped with the usual removable covers, which are removed during charging of the several ovens and placed in position to close the tops of the ovens during the entire coking operation.

The heat for coking the charges of coal in the several ovens or chambers 12 is derived from the flued heating walls 11, which,

as before mentioned, extend crosswise of the battery at the sides of the coking chambers. The crosswise regenerators 24 of the retort oven or battery are located at a lower level 5 than the aforesaid heating walls 11 and coking chambers 12 and in the present instance extend in parallelism beneath the coking chambers 12 and between the pillar walls 13. The interior meeting ends of the regenerators 10 are separated by a partition 25 which extends below the middle lengthwise line of the heating walls and all the way up from the mat of the battery to the bottom of the overlying coking chamber and from one to the other of the pillar walls 13. Each regenerator 24 is a chamber containing open brickwork commonly called checkerwork and indicated at 26 with a distributing sole channel 27 underneath the checkerwork of each regenerator, the channels forming the soles of and opening up into the checkerwork of their respective regenerators. These regenerators in alternation are heated by the 20 hot combustion products that are exhausted from the flame or combustion flues hereinbefore mentioned and then impart such heat to the medium that they feed into these flame flues. The regenerators are communicably connected with the flues by ducts 49, 25 and operate in conjunction therewith as fully explained in my said co-pending application Serial No. 376,126.

On the pusher side A of the battery, there is provided a pushing machine 79 of any 35 preferred construction, which pusher machine operates in the usual way to push the charges of finished coke from the horizontal coking chambers 12 at the ends of the coking periods in such chambers. It will be understood that the doors at both ends of each coking chamber are removed just prior to the pushing operation.

In accordance with the invention, the hot coke falls through the coking chamber opening on the coke side B of the battery and directly on to an inclined coke wharf 80 that extends downwardly from approximately the floor level of the several coking chambers. On this wharf, the hot coke is directly quenched by water supplied from a 45 hose 81 connected with any suitable source of water supply, and operable from a platform 89 extending along the lower end of the wharf 80. At the lower end of the coke quenching and discharge wharf or chute 80 is an endless conveyer 82 which is adapted to carry away the freshly quenched coke for the usual subsequent handling. Before and during the quenching operation, the coke is prevented from falling on to the 50 upper run of the conveyer by means of a pivoted gate 83 which is adapted to close the lower end of the aforesaid wharf or chute 80 and thus serves to regulate the 55 passage of coke from the coke wharf. The

gate 83 is provided with an operating lever 84 permitting it to be opened and closed as required. As shown in Fig. 3, the gates 83 may be disposed in series extending along the battery, of a size convenient for handling by their respective levers 84. Each gate is formed of reticular material as commonly employed in coke wharf constructions to permit the passage of water from the lower end of the wharf 80 while the 70 coke is held on the wharf by the gate. Beneath each gate 83 is a deflecting apron 85 pivoted at 86 and adapted to be operated by suitable means 87 consisting of a link 90 pivotally connected at 91 to an arm 92 that is rigidly secured at 93 to the apron pivot means 94. The other end of said link 90 is pivotally connected at 95 to an arm 96 that is rigidly secured at 97 to shaft 98 that is operated by the lever 84. One end of said 80 apron is flanged at 99 and the flanged end is arranged, when in the position shown in dotted lines in Figs. 2 and 3, to terminate into close proximity 100 to the conveyer 82 to prevent too great a fall of the fresh coke 90 onto the conveyer and thereby minimizing fracture of the coke. The deflecting aprons 85 may also be extended in series along the side of the battery and of such size as operating conditions and practice require. 95 When the gate is opened, the apron 85 is automatically and simultaneously swung into the position indicated by dotted lines in Fig. 2 so that it acts as a bridge or guide for directing the coke from the lower end 100 of the wharf 80 on to the conveyer 82. When the gate is closed, the apron 85 is automatically and simultaneously swung to the position indicated by full lines in said figure, to act as a guide for directing the water that discharges off the lower end of the wharf 80 into a discharge trough 88 located beneath the lower end of said chute and between the lower end of the chute and the conveyer 82. 105 This construction causes the water employed in the quenching operation to be discharged into a trough that is located on the coke side of the conveyer and substantially prevents the water from discharging on to the conveyer.

The invention as hereinabove set forth is embodied in a particular form of construction but may be variously embodied within the scope of the claims hereinafter made.

The coke oven features shown or described in the foregoing specification are made the subject matter of my original application Serial No. 376,126, filed April 23, 1920, of which this application is a division.

I claim:

1. A coke handling apparatus embodying: an inclined quenching wharf, a movable gate mounted at the lower end of the wharf and adapted to prevent passage of coke from the wharf, a coke conveyer beyond said

gate, and an apron automatically movable simultaneously with the gate into position for guiding the coke from the wharf to said conveyer, when said gate is moving to an open position for permitting discharge of coke from the wharf; substantially as specified.

2. A coke handling apparatus embodying: an inclined quenching wharf, a movable gate 10 mounted at the lower end of the wharf and adapted to prevent passage of coke from the wharf, a coke conveyer beyond said gate, a trough positioned beneath the lower end of the wharf for carrying off the quenching water, and an apron automatically movable simultaneously with the gate into one position for deflecting the quenching water into said trough when the gate is closed and automatically movable simultaneously with 15 the gate into another position for guiding the coke to said coke conveyer when the gate is opened to permit discharge of coke from the wharf; substantially as specified.

3. A coke handling apparatus embodying: an inclined quenching wharf, a gate movably mounted at the lower end of the wharf and adapted to prevent passage of coke from the wharf, a coke conveyor beyond said gate, a trough positioned beneath the lower end 20 of the wharf for carrying off the quenching water, an apron movable into one position for deflecting the quenching water into said trough when the gate is closed and movable into another position for guiding the coke 25 into close proximity to and onto said coke conveyor to minimize fracture of the coke when the gate is opened to permit discharge 30 of coke from the wharf and means connecting said gate and said apron whereby said gate and said apron are moved simultaneously.

4. A coke handling apparatus embodying: an inclined quenching wharf, a gate movably mounted at the lower end of the wharf 45 and adapted to prevent passage of coke from the wharf, a coke conveyor beyond said gate, a trough positioned beneath the lower end of the wharf for carrying off the quenching water, an apron movable into one position 50 for deflecting the quenching water into said trough when the gate is closed and movable into another position for guiding the coke to said conveyor when the gate is opened to permit discharge of coke from the wharf,

and means effecting movement of said gate and apron together.

5. A coke handling apparatus embodying: an inclined quenching wharf, a gate movably mounted at the lower end of the wharf and adapted to prevent passage of coke from 60 the wharf, a coke conveyor beyond said gate, a trough positioned beneath the lower end of the wharf for carrying off the quenching water, an apron movable into one position for deflecting the quenching water into said 65 trough when the gate is closed and movable into another position for guiding the coke to said conveyor when the gate is opened to permit discharge of coke from the wharf, means for moving said gate, and means effecting movement of said apron, said last mentioned means being operated by the power applied through said first mentioned means.

6. A coke handling apparatus embodying: an inclined quenching wharf, a gate movably mounted at the lower end of the wharf and adapted to prevent passage of coke from the wharf, a coke conveyor beyond said gate, a trough positioned beneath the lower end 80 of the wharf for carrying off the quenching water, an apron movable into one position for deflecting the quenching water into said trough when the gate is closed and movable into another position for guiding the coke to 85 said conveyor when the gate is opened to permit discharge of coke from the wharf, and a lever for moving said gate, and connections between said lever and said apron, said connections effecting movement of said 90 apron together with said gate.

7. A coke handling apparatus embodying: an inclined quenching wharf, a gate movably mounted at the lower end of the wharf and adapted to prevent passage of coke from 95 the wharf, a coke conveyor beyond said gate, a trough positioned beneath the lower end of the wharf for carrying off the quenching water, an apron movable into one position for deflecting the quenching water 100 into said trough when the gate is closed and movable into another position for guiding the coke to said conveyor when the gate is opened to permit discharge of coke from the wharf, and means for automatically moving 105 said gate and said apron together.

JOSEPH BECKER.
